YARN CONDITIONING AND CONTROL APPARATUS FOR TEXTILE MACHINES

Max Richter, West Reading, Pa., assignor to Textile Machine Works, Wyomissing, Pa., a corporation of Pennsylvania

Application December 24, 1937, Serial No. 181,639

9 Claims. (Cl. 66—125)

My invention relates to a novel means for treating or affecting yarn, particularly in association with yarn working or knitting machines, and including novel yarn tensioning and moistening means, and novel means controlling the level and supply of liquid for the moistening means, severally and in combination.

In certain yarn treating devices, such as the well-known moistening troughs of full fashioned knitting machines, it has been customary to employ combined tensioning and moistening means which cause accumulations of gum, lint and other matter in the troughs and it is necessary to clean them and to refill them. Generally, cleaning the troughs required unthreading the tension and moistening means therein.

In the prior art tensioning devices the direction and distance of travel of the yarn through the troughs are limited, whereby the degree of regulation which may be effected in the yarn tension is also limited.

Also, the maintenance of the liquid level in the troughs has been more or less troublesome, particularly in individual troughs of a multi-section machine having a plurality of these troughs individually associated with the respective machine sections.

Among the various suggestions for maintaining the levels uniform have been to employ troughs in liquid communicating relation to each other and reservoirs of the inverted bottle type, in refilling which the bottles are removed from position, carried to sources of liquid supply, and returned to position. These operations frequently result in spilling the liquid over various parts of the machine, breaking the bottles, delays in service and in other objectionable features.

An object of my invention is to provide a moistening trough structure for full-fashioned knitting machines arranged to facilitate the cleaning of the troughs.

Another object is to provide a yarn treating device through which yarn is threaded, the device comprising a receptacle for yarn treating liquid and a unit for supporting yarn guiding elements within the receptacle, said unit being so arranged with respect to the receptacle as to facilitate its removal and replacement in the desired position.

Another object is to provide novel adjustable guide means for effecting a combined yarn tensioning and moistening effect.

Another object is to provide novel means for overcoming the above indicated objections in yarn treating and tensioning devices, and in

maintaining the liquid level and supply thereof.

Another object is to provide novel valve means whereby several operations, ordinarily requiring individual attention as with a reservoir of the inverted type above mentioned, may be effected simultaneously.

Another object of my invention is to provide a yarn treating device through which yarn is threaded, the device comprising a receptacle for 10 a yarn treating liquid and a unit for supporting yarn controlling elements in the receptacle, and means whereby the unit and the receptacle can be separated without unthreading the yarn from the device.

Another object of the invention is to provide novel splash directing and guard means, means for the selective and detachable mounting of yarn guides, and other features.

With these and other objects in view, which will become apparent from the following detailed description of the illustrative embodiment of the invention shown in the accompanying drawings, my invention resides in the novel elements, features of construction, and arrangement of parts in cooperative relationship as hereinafter more particularly pointed out in the claims.

In the drawings:

Figure 1 is a rear elevational view of a multi-section full-fashioned knitting machine embodying the invention;

Fig. 2 is a detail view of a portion of the structure as viewed in Fig. 1, on a larger scale;

Fig. 3 is a view, substantially to the scale of Fig. 2, of the structure of Figs. 1 and 2, as viewed 35 cross sectionally of the machine from the right end of Fig. 1, parts being omitted, parts being in full lines, and parts being in dot-and-dash lines;

Fig. 4 is a detail perspective view of a splash 40 guard embodied in the invention;

Fig. 5 is a view, cross sectionally of the machine, taken substantially along the line 5—5 of Fig. 2 slightly enlarged thereover, of a device included in the invention for collecting excess 45 moisture from yarns and protecting portions of the machine;

Fig. 6 is a view partially in top plan and partially in section along the line 6—6 of Fig. 2 enlarged relative thereto;

Fig. 7 is a sectional view, parts being in elevation, taken substantially along the line 7—7 of Fig. 6, enlarged relative thereto;

Fig. 8 is a cross sectional view taken substantially along the line 8—8 of Fig. 7;

Fig. 9 is a view similar to a portion of Fig. 8,

showing parts of such portion in different operative positions;

Fig. 10 is a vertical plane sectional view, taken substantially along the line 10—10 of Fig. 6, enlarged thereover;

Fig. 11 is a view in side elevation, taken in the direction of the arrow "A" of Fig. 6, and drawn to the scale of Fig. 10, parts being broken away;

Fig. 12 is a vertical plane sectional view of a portion of the structure as viewed in Fig. 10, but with certain parts in different positions; and

Fig. 13 is an enlarged perspective view of the structure of Fig. 8;

In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines," copyright 1920, and in the "Reading" full fashioned knitting machine catalogues, copyright 1929 and 1935, published by the Textile Machine Works, Reading, Pennsylvania, and in a pamphlet entitled "Knitting Machine Lectures," published in 1935 by the Wyomissing Polytechnic Institute, Wyomissing, Pennsylvania.

Referring to Fig. 1, the parts of a multi-section full fashioned knitting machine therein shown are end frames 10, center frames 12, a back rail 14, and a center bed 15. These parts are united as a usual rigid base or framework for supporting the operating parts of the machine. Gallows 18, Figs. 2 and 3, on the center frames 12, are connected longitudinally of the machine, as by a bar 19, and support a moistening box unit M, such as shown in Patent No. 2,066,781, issued January 5, 1937, to Henry Janssen.

Troughs T, provided one for each knitting section of the machine, are connected in liquid communicating series relation to each other by conduits 22, and suspended, as by brackets 23 from another rod 24 on the gallows 18.

At the right hand end of the machine, as viewed from the rear in Figs. 1 and 2, brackets 27 and 28 (Fig. 3) secured to the adjacent gallows 18, vertically adjustably support a rod 29 on which is mounted a reservoir device B.

As viewed in Fig. 3, the structure further comprises a front rail 32, a cam shaft 33, a front bed 34, a needle lifting lever 38 on a shaft 39, a bracket 42 pivotally mounted on the lifting lever 38 supporting a needle bar assembly N, a sinker head assembly S, carrier rods R mounted in brackets, such as the bracket 43 on the center bed 15, yarn carriers or guide fingers 44 and 45, and yarn cones or supply packages 47 and 48 in the moistening boxes M.

The cone 47 supplies yarn 49, such as cotton yarn, to the carrier 45, which is a plating carrier, through an eyelet in the top of the unit M in which it is disposed, past a yarn guide rod 52 on portions 53 of gallows 18, through the trough T as hereinafter set forth, through a tension ring 57 vertically floatingly disposed on the yarn around one of a plurality of guides 58 that is supported on bracket arm portions 59 of the gallows 18, through a usual snapper 62, through an eyelet 65 in a receptacle 66, to be hereinafter more particularly pointed out, and past a yarn guide rod 63 on a bracket 64.

Yarn 67 is fed, at high speed, through an eyelet in the top of the box M, past a guide rod 68 on the

bracket 53, through the trough T, constituting part of the invention, through a tension ring 69 on another of the guides 58, through a snapper 72, through an eyelet 71 in the receptacle 66, and past a guide rod 73 in the bracket 64 to the carrier 44.

Referring further to Figs. 5, 6, 7, 8 and 13, each trough T comprises a plain oblong box-like receptacle 74, as of sheet metal, for the reception of a liquid, such as water, for maintenance at a level L, by the reservoir device B, through nipples 75, the conduits 22, and a conduit 76.

As better seen in Fig. 13, a unit U, for readily removable direct contact telescopic fitting relation to the receptacle 74 in the upper part of the latter, is generally of elongated rectangular substantially C-shape fitting the plan contour of the receptacle 74 having end members 77 fitting the short inner sides of the receptacle ends, and an intermediate lengthwise member 78 extending parallel to one of the long sides of the receptacle in slightly spaced relation thereto. Each of the members 77 is of substantially L-section (Fig. 7) having an upright portion 79 and a horizontal portion 80 having end brace portions 90 (Fig. 13). The end members 77 each have clip portions 81 arranged so that, when the unit U is lowered into the receptacle 74, the clip portions 81 will embrace the top edges of the receptacle 74, and hold the unit in place with its bottom above the bottom of the receptacle. Vertical sheet metal members 82 of channel section are welded, or otherwise secured, to the upright portions 79 of the members 77, and spaced from each other by distances substantially equal to the widths of the channels, whereby not only to provide a channel between the walls of each member 82, but also to provide similar channels between certain of the members 82 for the selective reception of one or more cylindrical float elements 83, parallel to the longitudinal box sides, each of itself being floatable and having its ends in channels formed by the members 82 at opposite ends of the trough. The floats 83, as shown, are constructed from cylindrical glass tubes each having both ends sealed, and at least one end 85 of polygonal cross section, or otherwise constructed, whereby the tube can float vertically in its end channels, but cannot have rotative movement by reason of the relation to the polygonal or otherwise constructed flat end or ends 85 to the channel members 82. Being disposed over the horizontal portions 80, when the unit U is lifted from the receptacle 74, the floats are lifted with it.

Sheet metal strips 84 of substantially Z-section (Fig. 7), secured to the end members 77 across the tops of the channel members 82, have fingers 86 providing notches for the reception of yarn guide rods 88. The fingers 86 have side projections 87 (Figs. 8 and 9) constituting slight constrictions against placing the rods 88 into, or removing them from, the notches, the fingers being of such resiliency, and the projections being so proportioned or spaced from each other relative to the diameters of the rod 88 that the rods can, by a comparatively light manually applied force, be forced into, and removed from the notches, with a substantially snap action past the projections 87. However, the feature operates such that the rods 88 cannot readily be accidentally jarred or otherwise removed from positions in the notches, or a rod cannot be lifted out of position by the yarn where the latter passes under the rod instead of over each of the rods, as does the

yarn 49 (Fig. 13) which is tensioned but not treated or moistened in the trough T.

A sloping platform 89 (Figs. 8, 9 and 13) is provided on the intermediate member 78 for the optional reception of a felt or felts 92, along the top surface of one of which or between two of which the yarn 67 can pass for the removal of water from the yarn, or felt can be omitted and the yarn guided through space above the platform, as controlled by a guide rod 93 and one of a battery of eyelets 94. The rod 93 is supported on a ledge 97 (Fig. 13) of the platform 89 between a portion 98 and a side wall (Fig. 8) of the next adjacent channel member 82. The felt 92 has ends 95 depending over the ends of the platform 89 to positions either above or below the liquid level, and is held in place by lugs 96 projecting upwardly from the intermediate member 78.

The eyelets 94, and similar eyelets 99, are mounted on metal strips 102 and 103, respectively, the eyelets 99 being for leading yarns into the trough T, and the eyelets 94 for leading the yarns out of the trough. These eyelets, although producible from any of various materials, are, in this instance, of vitreous material, such as porcelain or glass. Each strip 102 and 103 is indicated in this instance, as adapted to support ten of its respective eyelets, although here also, the number may be varied for different applications. Further, the strips 102 and 103 are provided, adjacent to their ends, with spring clips 107 for readily removably embracing the top margins of the upright front and back walls of the receptacle 74, this arrangement being more rigid, permanent and effective than a former structure in which a single clip is used for each eyelet. A splash guard 108 (Figs. 4, 6, 7 and 8), of metal having some resiliency and provided with return bent or crimped reinforced edges 109, is bowed or sprung in place, as shown, over the high speed yarn or yarns which may be passed through the trough, and which throw off spray. The guard 108 is only of sufficient width to adequately cover the high speed yarns, and may be adjusted or shifted along the receptacle to provide for placing these yarns in any desired positions.

In the operation of any of the troughs T, one or more of the rods 88 are adjusted parallel to the liquid level in any suitable arrangement in the notches 87, and one or more of the floats 83 are adjusted parallel to the liquid level by being placed in any selected of the channels formed by the members 82, whereby to obtain any one of various yarn tension values, in combination with the yarn treating or moistening effect which the yarn receives as it passes under the float or floats 83 and engages the latter in the liquid, which combined effect is maintained substantially constant by maintaining the level L substantially constant. Substantial lowering of this level, of course, would lower the float or floats and vary the yarn tension.

In the arrangement of Fig. 9, the last float 83 and the last guide rod 88, to the right of the figure, are so arranged as to throw a length of the yarn backwardly on itself near its position of final departure from the liquid whereby to reduce or prevent the extension of splash in the direction of departure of the yarn from the trough.

The device B, see particularly Figs. 10, 11 and 12, for maintaining the liquid level L and the yarn tension constant, comprises a reservoir 112 of the inverted bottle type held in place at the

top, which is its inverted bottom, by a bracket 114 secured to the rod 29 as by a set screw, and having branches or arms 117 over the reservoir, and fingers 118 depending from the outer ends 5 of the arms 117 about the periphery of the reservoir or bottle bottom to hold the reservoir laterally in place. Springs 119 in recesses of the arms 117 act as yieldable cushions and binding means, assisting in preventing damage to the 10 reservoir, when it is of glass, as shown, and tending to hold it in place. A valve attachment V comprises a metal body having a cup-like portion 122 for the reception of the mouth end 123 of the neck 124 of the bottle or reservoir 112, a gasket 127, of rubber, cork felt, or other yielding 15 material being provided between the cup 122 and the mouth 123, as a cushion and seal for the latter. A tube 128, constituting a continuation of an air passage 129, is held in place in an upright 20 tubular projection 132 at the bottom of the cup 122. A tubular element 133, depending from the cup 122, provides a liquid feed passageway between the reservoir 112 and a receptacle 134, and is, in effect, an extension, of reduced diameter, 25 of the mouth 123 at approximately the level L of the liquid in the receptacle 134, which is connected to the troughs T by the conduit 76. A passageway 137 extends downwardly through the bottom of the cup 122 and laterally to a liquid 30 supply pipe 138 to which it is connected by a connector 139.

A conical valve element 142, having an operating handle 143, for movement between stops 145 (Fig. 11) and held in position by a nut and 35 washer device 144, has radial orifices 147, 148 and 149 opposite the passageways 137, 129 and 133, respectively, the orifices 147 and 148 being parallel to each other, and disposed ninety degrees from the orifice 149 about the axis of the cone 40 142 whereby, at one time, when the handle 143 is in the position of Fig. 12, to simultaneously connect the reservoir 112 to the supply line 138, open the air passageway 129, and close the feed 45 passageway 133, and, at another time, when the handle 143 is in the position of Figs. 10 and 11, to simultaneously disconnect the reservoir 112 from the supply line 138, close the air passageway 129, and open the feed passageway 133. When the handle 143 is in the position of Fig. 12, the 50 structure allows air to escape from the bottle, and prevents liquid from feeding therefrom to the receptacle 134, when the bottle is being re-filled through the supply passage 137. When the handle is in the position of Figs. 10 and 11, the 55 reservoir operates as an ordinary bottle, which, since its effective mouth at the lower end of the element 133 is sealed by the liquid in the receptacle 134, will not allow the liquid to flow from the bottle until the level L recedes from the 60 mouth to admit air. When the level L is as indicated in Fig. 10, the pressure of the liquid in the reservoir and the atmospheric pressure on the liquid in the receptacle 134 balance each other such that liquid does not feed until, as 65 aforesaid, the level L recedes slightly below the effective bottle mouth.

In the invention, by the use of the reservoir B in cooperation with the floats 83, the yarn tension is maintained substantially constant, and 70 by reason of the floating action of the floats 83, the yarn is submitted to, or affected by, the liquid in a uniform manner, irrespective of minor changes in the liquid level, since irrespective of this level, substantially the same length of yarn about the float is immersed at all times. In

other words, with the liquid level constant, the perpendicular distance, between each float 83 and the guide rods 88, is maintained constant. This condition ensures engagement of unvarying lengths of the yarn on the peripheries of the floats, and thereby unvarying lengths below the liquid level, and also maintains unvarying lengths of the yarn on the peripheries of the rods 88, so that the reservoir device B, in maintaining the liquid level constant, thus has a definite and direct yarn tension function, in addition to its yarn treating and other functions.

Since the reservoir holds a substantial amount of liquid, which is visible at all times, it is easy for an operator to operate the device when necessary or at times to suit his convenience, by a simple movement of the handle 143. This feature avoids stopping the machine, disassembling any parts, spilling the liquid or breaking the reservoir.

As a precaution, not likely to be called upon to operate, an overflow pipe 150 (Figs. 5, 7 and 13) is provided in each trough T, such that, if for any reason, a continuous supply of liquid should flow from the supply line 138, through the reservoir B, and into the troughs T, it will flow through the pipes 150 into the receptacle 66 (Figs. 3 and 5). The receptacle 66, one of which is provided for each machine section, is suspended from the gallows 18, as by hooks 152, and extends upwardly and forwardly of the machine under paths of the yarn and above certain of the machine mechanism over which the yarn extends. This arrangement protects the mechanism against excess moisture from the yarn. The eyelets or yarn guides 65 and 71, through which the yarns 49 and 61 pass, respectively, thereby constitute the receptacle 66 both as yarn guide means and as means for collecting excess moisture. A conduit 154, shown as of V-section and suspended from the gallows 18, as by a connector 155, extends along the machine to carry off excess moisture which it receives from an opening or openings 156 in each receptacle 66, and discharges through a drain conduit 157.

Of course, the improvements specifically shown and described by which I obtain the above results, can be changed and modified in various ways without departing from the invention herein disclosed and hereinafter claimed.

I claim:

1. In combination in a yarn treating device, a receptacle for a yarn treating liquid, a plurality of elements in the receptacle for guiding and affecting the yarn in said treatment, and means whereby the receptacle may be readily entirely separated from said elements without requiring rethreading of the yarn relative to the device, comprising a unit for supporting said elements, said unit having a portion substantially telescopically fitting inner sides of the receptacle providing for the removal of the unit and said elements from the receptacle.

2. In a yarn moistening device for a full fashioned knitting machine, in combination, a rectangular container for a liquid yarn wetting agent, a rectangular unit supported by said container comprising a frame arranged to telescopically extend into the container and having yarn guiding elements detachably connected therewith, and means carried by said unit for supporting a plurality of longitudinally extending floats within said container for guiding yarns through said liquid.

3. The combination with a yarn working

means of an arrangement for moistening yarn going to said working means comprising container means for a moistening liquid, a group of parallel members movable from one operative position to another and arranged to guide said yarn beneath said moistening liquid, a second group of parallel members movable from one operative position to another arranged above said moistening liquid to receive the yarn from the members of said first group, and means for holding said members in operative position in use providing more recesses for the ends of said members than there are members, whereby said members may be shifted from one operating position to another to change the tension on the yarn.

4. In combination in a yarn conditioning device, trough structure providing for the reception of yarn and the passage of yarn from the trough, means in the trough for controlling tension of the yarn and treatment of the yarn by a liquid including tension means and float means affecting the yarn, a reservoir, passageway means for liquid feeding from the reservoir to the trough, means for connecting the reservoir to a supply pipe line from a liquid source, air passageway means providing for escape of air while supplying the reservoir with liquid, and valve means for, at one time, connecting the reservoir to the supply line, opening the air passageway and closing the feed passageway, and, at another time, disconnecting the reservoir from the supply line, closing the air passageway and opening the feed passageway.

5. In combination in a yarn conditioning device, trough structure providing for the reception of yarn and the passage of the yarn from the trough, means in the trough for controlling tension of the yarn and immersion of the yarn in a liquid including adjustable tension means and float means adjustable for operation in selected positions, a reservoir, passageway means for liquid feeding from the reservoir to the trough, means for connecting the reservoir to a liquid supply pipe line, air passageway means providing for escape of air while supplying the reservoir with liquid, and a three-way valve for, at one time, connecting the reservoir to the supply line, opening the air passageway and closing the feed passageway, and at another time, disconnecting the reservoir from the supply line, closing the air passageway and opening the feed passageway.

6. A yarn conditioning device comprising in combination, a reservoir, a structure for exposing yarn to a liquid to effect treatment thereby, a passageway from the reservoir to the structure, means for connecting the reservoir to a liquid supply line, air passageway means providing for escape of air while supplying the reservoir with liquid, and a three-way valve for, at one time, connecting the reservoir to the supply line, opening the air passageway and closing the passageway from the reservoir to the structure, and at another time, disconnecting the reservoir from the supply line, closing the air passageway and opening the passageway from the reservoir to the structure.

7. In combination in a yarn conditioning device, a receptacle, and means providing for the passage through a liquid therein of yarn from a yarn supply to a yarn working mechanism including yarn tensioning means, and a flexible splash guard element of bowed form sprung into position on the receptacle along a path of yarn movement therein.

8. In combination in a yarn conditioning device, a receptacle, means providing a plurality of paths for yarns through a liquid in the receptacle, and a splash guard means mounted for movement between positions over certain of said paths independent of others.

9. In combination in a knitting machine having loop forming mechanism and yarn supply supporting means, of yarn moistening means

including a liquid overflow device, means for feeding yarn from a supply on said supporting means through said moistening means to the loop forming mechanism along a path, and means for receiving liquid from said overflow device and having a portion under said path for collecting excess moisture from the yarn thereon.

MAX RICHTER.
